HOISTING TONG

Lee Nelson, Texas City, Tex.

Application April 12, 1943, Serial No. 482,794

2 Claims. (Cl. 294—86)

This invention relates to a hoisting tong.

An object of the invention is to provide a tong of the character described specially adapted for lifting heavy metal plates, beams and the like.

Another object of the invention is to provide a tong having opposing fixed jaws provided with downwardly converging faces on which are mounted wedge shaped slips whose inner sides are formed with teeth to engage the load between the slips.

A further object is to provide, in a tong, releasable means for automatically locking the slips in engagement with the load to prevent the unintentional release of the load.

With the above and other objects in view the invention has particular relation to certain novel features of construction, operation, and arrangement of parts, an example of which is given in this specification and illustrated in the accompanying drawing wherein:

Figure 1 shows a side view of the tong partly in section.

Figure 2 shows an edge view.

Figure 3 shows a fragmentary cross sectional view taken on the line 3—3 of Figure 1.

Figure 4 illustrates the ratchet faces of the locking dogs employed and

Figure 5 illustrates one application of the tong to the load.

Referring now more particularly to the drawing wherein like numerals of reference designate the same parts in each of the figures, the numerals 1, 1 refer to opposing fixed jaws which are formed integrally, at one end, to the eye 2. These fixed jaws have the faces 3, 3 which converge toward the free ends of the jaws.

In the inner sides of the jaws 1 are the longitudinal dove tailed grooves 4, 4 which extend the full length of the faces 3. There are the wedge shaped slips 5, 5 which are dove tailed into the grooves. The inner sides of the slips are parallel and toothed to engage and grip the plate 6, or other load, between them.

Each jaw 5 has the projecting side pins 7, 7 adapted to engage the inwardly projecting ends of the screws 8, 8 to prevent the slips from dropping out. The screws 8 are threaded through the jaws 1 as shown in Figure 3 and may be unscrewed and their inner ends retracted out of the way of the pins 7 when it is desired to remove the slips.

In use a single tong may be swung from a lifting cable 9 and may be engaged with the plate 6 or with a beam or other load and upon elevation of the tong the slips 5 will move down-

wardly along the faces 3 and inwardly into gripping relation with the load; or a pair of tongs may be engaged with the plate as shown in Figure 5 and connected to the ends of the bridle

10 which, in turn, may be lifted by the cable 9.

Provision has been made for locking the slips in engagement with the load to prevent premature release of the load. For this purpose the outer side of each slip is provided with the upwardly pitched ratchet teeth, 11. Each fixed jaw 1 is provided with a bore 12 to receive a cylindrical dog 13. The inner end face of this dog has transverse ratchet teeth pitched oppositely from that of the pitch of the corresponding teeth 11.

Screwed into the outer end of the bore 12 there is a gland 14 having the inside longitudinal grooves 15. Each dog 13 is attached to an outwardly extended shank 16 which extends out through said gland and whose outer end is formed into a grip 17. The shank has a cross key 18 whose ends extend into the grooves 15.

Located within the bore 12 and surrounding the shank and interposed between the gland 14 and the dog 13 there is a strong coil spring 19.

As the tong is applied to the work the slips 5 will move upwardly along the faces 3 and outwardly to permit the plate 6, or beam, to readily enter between the slips. While applying the tong to the work the dogs 13 should be pulled outwardly until the cross keys 18 are released from the grooves 15 and then turned so that the ends of the cross keys will engage the outer ends of the bushings 14. The dogs will thus be held retracted with the teeth of the dogs out of engagement with the teeth 11. This will permit the slips 5 to move freely. When the plate or beam has been inserted between the slips the shanks 16 should be turned to align the cross keys with the grooves 15 and the springs 19 will move the dogs inwardly into active position. Upon an upward pull of the cable 9 the slips 5 will move downwardly along the faces 3 and inwardly into engagement with the load, the teeth 11 ratcheting past the teeth of the dogs 13 and said slips will be locked in said position by said dogs so that the tong will not accidentally or prematurely release the load.

It will be noted from an inspection of Figure 4 that the teeth of one dog 13 are staggered with respect to the teeth of the other dog. This has been done to insure that at least one dog will engage with the teeth of the corresponding slip. Otherwise it might happen that the crests of the teeth of both dogs might rest on the crests of the

corresponding teeth || thus allowing a sufficient release movement to both slips to permit release of the load. If either of the slips is locked against movement the other slip, even though not locked by its dog, will be held against release movement by the engagement of its teeth against the load.

The drawing and description are illustrative merely while the broad principle of the invention will be defined by the appended claims.

What I claim is:

1. A hoisting tong comprising a pair of spaced jaws anchored together at one end and having their other ends free, said jaws having inside faces which converge toward said free ends, wedge shaped slips mounted on said faces and having dovetailed connections therewith and mounted to move into gripping relation with a load between the slips, one of said jaws being provided with a bore, a gland secured in the outer end of the bore and having an inside longitudinal groove, a dog in said bore having an outwardly extended shank which extends through the

gland, a cross key on the shank whose end extends into the groove, a yieldable member in the bore normally holding the dog in engagement with the corresponding slip, said key being engageable with the outer end of the gland, when the shank is pulled outwardly and turned, and forming means for locking the dog disengaged from the slip.

2. A hoisting tong comprising a pair of spaced jaws anchored together at one end and having their other ends free, said jaws having inside faces which converge toward said free ends, wedge shaped slips mounted to move on said faces into gripping relation with a load between the slips, said slips having external ratchet teeth, dogs mounted on the jaws and having ratchet teeth, yieldable means normally holding the teeth of the dogs in engagement with the teeth of the slips, the teeth on one side of the tong being staggered with respect to the teeth on the other side thereof.

LEE NELSON.
